UNITED STATES PATENT OFFICE.

ALVIN G. SHERMAN AND ALBERT MEADOWS, OF DETROIT, MICHIGAN, ASSIGNEES TO
DETROIT VAPOR STOVE COMPANY, OF DETROIT, MICHIGAN, A CORPORATION OF
MICHIGAN.

GAS-COCK ASSEMBLY.

Application filed November 15, 1923. Serial No. 674,893.

To all whom it may concern:

Be it known that ALVIN G. SHERMAN and ALBERT MEADOWS, citizens of the United States, residing at Detroit, in the county 5 of Wayne and State of Michigan, have invented certain new and useful Improvements in Gas-Cock Assemblies, of which the following is a specification.

This invention relates to a handle assembly, and more particularly to one which is adapted to be secured to the plug of a gas valve used in regulating the flow of gas to the burner of a standard gas range.

Much difficulty has been experienced in 15 the past in the construction of these handles due to the fact that the stove bolt used in securing the handle to the plug backs up on the thread and the porcelain handle becomes loose. It is necessary for the stove 20 bolt to back up only a little in order to loosen the handle, and this difficulty can only be overcome by a frequent use of the screw-driver in tightening the stove bolt.

It is the purpose of our invention to eliminate the possibility of the handle coming loose when the stud that is screwed into 25 the plug of the gas cock backs up slightly on its threads. Another purpose of the invention is to provide a special form of screw 30 machine product which can be rigidly secured within the porcelain handle and can be threaded into the plug of the gas cock by applying the necessary force to an integrally formed nut portion of the screw 35 machine product positioned between the porcelain handle and the plug.

This presents a very neat appearing handle and provides a smooth handle portion, eliminating the exposed head of a 40 stove bolt and also provides a construction that can be very easily tightened up at different times. Furthermore, the backing up of the thread of the screw machine product in the plug will not cause the handle 45 to become loose as is the case with the present form of handle embodying a long stove bolt.

In the drawings:

Fig. 1 is an elevational view of a standard gas cock provided with our improved handle.

Fig. 2 is an enlarged vertical section through the handle and a fragmentary portion of the plug.

Fig. 3 is a transverse section taken on the 55 line 3—3 of Fig. 2.

Fig. 4 is an elevational view of the handle and stud.

Fig. 5 is an end view of the same, showing the angular nut portion for applying 60 a tool to thread the same into the plug.

The standard gas cock used on present day gas ranges consists of a barrel *a*, and a plug *b*, which fits into the barrel and is adapted to be rotated to open or close 65 the gas passageway for regulating the flow of gas through the gas cock. The upper end of the plug *b* is provided with a spherical portion *c* provided with a tapped hole 70 *d* for a purpose later to be described.

Our improved handle assembly consists of handle, preferably porcelain, *e*, provided with a cored hole *f*. We use a special form of screw machine product or stud, which is provided with an enlarged nut portion 75 *g* intermediate the ends thereof and has a fluted portion *h* on one side of the nut which is adapted to be inserted into the hole *f* carried by the handle. To secure the stud to the handle we cement this stud 80 *h* within the hole or recess *f*, the annular grooves carried by the stud preventing a longitudinal withdrawal of the stud from out of the handle. As will be seen from Fig. 2 to Fig. 4, the nut portion of the 85 screw machine product is positioned adjacent the inner end of the handle.

On the opposite side of the nut portion *g*, of the stud and on the side farthest removed from the handle, there is a threaded portion *i* which is adapted to be threaded 90 into the tapped hole *d* carried by the plug *c*. In order to assemble the handle with the plug, the stud *i* is screwed into the plug and a wrench or other suitable tool 95 is applied to the angular nut portion of the screw machine product to tighten the handle assembly to the plug. It is evident from the foregoing description that the handle portion is rigidly supported on the 100 screw machine product at all times. If the stud *i* should back up a trifle on its threads the porcelain handle will not come loose as is the case with other handles.

We form the handle with longitudinal 105 grooves *m* in the cored hole *f*. The purpose of this longitudinal groove is twofold, and it will function not only as an air vent when

- the cement is forced into the hole and securing the stud *h* therein, but the cement will flow into the groove and securely key the cement and stud to the handle. It is possible that when the handle has been in use for some time the cement will come loose from the porcelain and allow the handle to rotate about the stud if it were not for the tongues formed on the cement filler.
- 10 When a person grasps this handle, he quite often tends to twist the same and the constant application of this strain is liable to break the union between the cement and the porcelain if it were not for the tongue and 15 groove joint between the same.

Our handle construction presents a pleasing appearance to the eye and is very neat in construction. It does not expose any bolt heads to the outside view. The nut portion 20 *g* can be nickled so as to conform to the nickled surface of the gas cock. In the present form of handle assembly using a stove bolt, the head of the bolt becomes roughened by continual use of the screw- 25 driver in tightening up the same, and often this roughened surface will scratch or cut the hand of the person who is grasping the handle for regulating the flow of gas to the burner. But in our handle assembly there is 30 no possible chance of a person cutting his hand since there is no break in the smooth contour of the porcelain handle.

What we claim is:

1. In a cock assembly, the combination of 35 a plug provided with a tapped hole, and a handle provided with a stud secured therein and projecting from the inner end thereof, said stud provided with an angular nut portion adjacent to the inner end of the handle, 40 and a projecting threaded stud portion adapted to be screwed into the said tapped

hole, thereby positioning the nut portion between the handle and the plug.

2. In a cock assembly, the combination of a plug provided with a tapped hole, a handle 45 provided with a recess, and a screw machine product provided with an angular nut portion, and threaded and grooved portions disposed respectively on opposite sides of the nut portion, the grooved portion 50 cemented within the recess carried by the handle and the other stud portion adapted to screw into the tapped hole of the plug.

3. In a cock assembly, the combination of a plug provided with a tapped hole, and 55 a handle having a screw machine product secured therein and provided with an enlarged angular nut portion adjacent the inner end of the said handle and a projecting threaded stud portion adapted to screw into 60 the tapped hole of the plug whereby the said angular nut portion carried by the screw machine product is positioned between the handle and the plug.

4. In a cock assembly, the combination of 65 a plug provided with a tapped hole, a handle provided with a recess having a longitudinal groove in the wall formed by said recess, and a stud provided with an enlarged nut portion intermediate the ends thereof, a 70 fluted portion on one side of the nut and a threaded portion on the other side of the nut, the fluted portion of said stud adapted to be cemented in the grooved recess of the handle whereby the cement flows into the longitudinal groove to key the handle on the stud to prevent relative rotating movement of the same.

In testimony whereof they have affixed their signatures.

ALVIN G. SHERMAN.
ALBERT MEADOWS.
